UNITED STATES PATENT OFFICE.

ALFRED RANGOD PECHINEY, OF SALINDRES, GARD, FRANCE, ASSIGNOR
TO THE WELDON'S CHLORINE PROCESSES COMPANY, (LIMITED,) OF
WESTMINSTER, ENGLAND.

APPARATUS FOR MAKING CHLORINE.

SPECIFICATION forming part of Letters Patent No. 403,445, dated May 14, 1889.

Application filed May 21, 1888. Serial No. 274,580. (No model.) Patented in England August 1, 1885, No. 9,225.

To all whom it may concern:

Be it known that I, ALFRED RANGOD PECHINEY, a citizen of the Republic of France, residing at Salindres, (Gard,) in the Republic 5 of France, have invented certain new and useful Improvements in Apparatus for Making Chlorine out of Contact with the Products of the Combustion of the Fuel Employed, (for which I have received Letters Patent in Great 10 Britain, No. 9,225, dated August 1, 1885,) of which the following is a specification.

In an application filed the 16th day of May, 1886, Serial No. 203,336, I described an apparatus for heating solid substances out of contact with the products of combustion of the fuel employed.

The apparatus which constitutes the present invention differs from the particular form of apparatus described in the specification of 20 that application, especially in two particulars. Both in the former apparatus and in the apparatus which constitutes the present invention the furnace proper consists of a series of working-chambers; but whereas in the former 25 apparatus the working-chambers are so arranged and disposed that the products of combustion employed to heat them traverse successively every chamber of the series, either entering at the top of the first chamber, 30 passing from the bottom of the first chamber into the lower part of the second chamber, then passing from the top of the second chamber into the upper part of the third chamber, and so on, or entering at the bottom of the 35 first chamber, passing from the top of the first chamber into the upper part of the second chamber, then passing from the bottom of the second chamber into the lower part of the third chamber, and so on successively, in the 40 apparatus which constitutes the present invention the products of combustion employed to heat its working-chambers do not pass from one of those chambers to another of them, entering one of them by its lower or upper 45 extremity and the next by its upper or lower extremity, and so on successively, but all the working-chambers communicate by the same extremity of each of them with a common combustion-chamber, and products of combus-

tion enter each of the working-chambers directly from the combustion-chamber, entering 50 all the working-chambers either at the upper extremity of each of them or at the lower extremity of each of them, and the products of combustion which have traversed one working-chamber not passing on to another working-chamber, but passing directly from the one working-chamber which they have traversed into other apparatus, as will be herein-after explained. Secondly, whereas the former 55 apparatus included two fixed regenerators, in the apparatus which constitutes the present invention there is substituted for those two fixed regenerators a movable burner, which is preferably, though not necessarily, a regen- 60 erator also.

The accompanying three sheets of drawings represent the apparatus which constitutes the present invention when that apparatus is so disposed that the products of combustion employed to heat its working-chambers enter those chambers at the upper extremity of each of them. They show an apparatus having four working-chambers. It 70 will be well understood, however, that the 75 number of working-chambers per apparatus may be more or less than four, and also that the products of combustion employed to heat its working-chambers may enter each of those chambers at its lower extremity instead of at 80 its upper extremity, as in the apparatus shown in the drawings.

While applicable to many other purposes also, the apparatus which constitutes the present invention is especially useful for decomposing solid chemical compounds by heating them in a current either of air or of any gas or gases, or of steam or other vapor, or of any mixture of a gas or gases with a vapor or vapors. In the following description it will be 85 supposed that the apparatus is employed for heating magnesium oxychloride in a current of air.

The apparatus is illustrated by the accompanying drawings.

Figure 1 shows a vertical section of the furnace proper and movable regenerative burner. Fig. 2 shows a horizontal section of the fur-

nace proper and movable regenerative burner. The upper part of this section is taken along the line C D, Fig. 1, and the lower part of it along the line E F, Fig. 1. Both in Fig. 1 and 5 in Fig. 2 the movable regenerative burner is shown in the position in relation to the furnace proper which it occupies during the operation of heating up the working-chambers of the latter. Fig. 3 shows a vertical section 10 of the furnace proper, taken at right angles to the section shown in Fig. 1. Fig. 4 is a horizontal section along the line G H, Fig. 3. Fig. 5 is a vertical section of the furnace proper after its working-chambers have been heated 15 up, the movable regenerative burner removed, and the working-chambers of the furnace proper charged with the solid material which is to be treated in them. Fig. 6 is a horizontal section taken along the line I J, Fig. 5. 20 Fig. 7 is a vertical section of the movable regenerative burner, taken along the broken line K L, Fig. 1.

The same letters refer to the same parts of the apparatus in all the figures.

25 In the following description it will be supposed that the chlorine-yielding body which is heated in a current of air is oxychloride of magnesium.

30 A A A A are four narrow working-chambers having very thick walls. The upper extremity of each chamber A opens into the combustion-chamber B. The lower extremity of each chamber A communicates with one of the four horizontal channels a a a a.

35 D, Figs. 1 and 7, is the movable regenerative burner. It consists of a system of cast-iron pipes contained in an envelope of masonry, which envelope of masonry is incased with iron plates and securely armatured. The 40 cast-iron pipes are of rectangular section, and each of them is divided by two vertical partitions into three compartments, i o u. The central compartments, o o o, &c., convey gaseous fuel into the combustion-chamber B, and 45 the side compartments, i and u, convey air into the combustion-chamber.

The gaseous fuel is supplied by the main pipe, upon which is the valve N, Fig. 2, from which main pipe it passes by the pipes V and 50 C, Fig. 2, into the flue c, Figs. 1 and 7, from which flue c it enters the compartments o o o by apertures at the bottom of those compartments. Having reached the upper extremity of the compartments o o o, the gaseous fuel

55 issues into the combustion-chamber B by the small pipes d d d, Figs. 1, 2, and 7. The air which is to burn the gaseous fuel enters at the bottom of the compartments i and u, and, having risen to the upper extremity of those 60 compartments, issues into the combustion-chamber by the wide flat pipe T, Fig. 1. It will be seen from Figs. 1 and 7 that the small pipes d d d pass through this wide flat pipe T, and that the small pipes d d d are a little 65 longer than the flat pipe T.

The pipe V, Fig. 2, is fixed to the main pipe, on which is the valve N. The pipe C, Fig. 2,

is fixed to the movable regenerative burner. When the movable regenerative burner is in the position in relation to the furnace proper 70 in which it is shown in Figs. 1 and 2, the pipe C communicates with the pipe V at the point U, Fig. 2. The joint at U is one which can be readily made and readily unmade.

From the combustion-chamber B products 75 of combustion enter the narrow working-chambers A A A A by the upper extremity of each of them. After traversing these chambers downward they pass off by the four horizontal channels a a a a into the movable regenerative burner. Following the direction 80 of the arrows in Fig. 1, they first pass upward through the flues Z Z Z, Figs. 1 and 2, and then travel downward, circulating round the rectangular cast-iron vertical pipes which 85 have been described, and passing between those rectangular pipes, and then passing off from the burner by the pipe P, Figs. 1 and 2, which conveys them to the flue G, Fig. 1. In thus passing downward through the movable 90 burner they heat the gaseous fuel which is passing upward through the compartments o and the air which is passing upward through the compartments i and u.

The pipe P, which is fixed, communicates 95 with the flue by which products of combustion pass off from the movable burner by the piece Q, the lower part of which fits into the upper part of the pipe P in such manner that the piece Q can be raised or lowered by the 100 lever S.

It will be seen from Figs. 1 and 7 that the whole regenerative burner is mounted on wheels. When the burner is in the position 105 in relation to the furnace proper in which it is shown in Figs. 1 and 2, the wheels of the movable regenerative burner stand on rails upon a truck, K K, Figs. 1, 2, and 7. This truck also stands on rails. When the truck is drawn a short distance from the furnace 110 proper, the rails on the truck K become in such a position in relation to other rails, one of which is shown at r, Fig. 1, that the burner can be transferred to those other rails and drawn along them onto another truck 115 installed opposite another furnace. Thus while oxychloride of magnesium is being heated in a current of air in one furnace the movable regenerative burner can be employed to heat 120 up the working-chambers of another similar furnace.

The working of the apparatus will now be easily understood.

When the four working-chambers A A A A have been heated to a sufficient temperature, 125 the first step is to close the valve N, Figs. 2 and 3, and so to cut off the supply of combustible gas to the movable regenerative burner. The pipe C, Figs. 1 and 2, must then be disconnected from the pipe V, Fig. 2, the 130 pipe P must be lowered, and then the truck on which the whole regenerative burner is supported must be drawn away from the furnace proper until the wheels of the burner

are opposite the rails, one of which is marked *r* in Fig. 1. The openings by which products of combustion have entered the working-chambers must now be closed by the doors *E* Figs. 1 and 5, and the opening by which those products of combustion have passed off from the working-chambers must be closed by the doors *F* Figs. 1, 5, and 6. One door *E* and one door *F* suffice for the whole furnace, as will be seen as regards the door *F* from Fig. 6. The doors *E* and *F* are hung on hinges, as will be understood from Fig. 1, and when they are in position to close the openings to which they correspond they are pressed 10 tightly against their seats by screws, as shown in Figs. 5 and 6. The working-chambers *A A A A* have now to be charged with oxychloride of magnesium in small pieces from a tip-wagon charged therewith, which has been 15 previously brought into position on the top of the furnace. The oxychloride enters the working-chambers by the opening *H H II*, Figs. 1, 3, and 5. The cover or door which closes this opening is seen in Figs. 1, 3, and 5, 20 but is not marked with any letter. This cover having been removed, a hopper is brought over the opening *H* and oxychloride is then poured into the hopper, whence it falls into the working-chambers *A A A A*. The door 25 or cover of the opening *H* is then rapidly replaced, and air is then admitted into *A A A A* through apertures in the door *E*, which apertures are not shown in the drawings. The oxychloride rapidly becomes heated by 30 absorption of some of the heat previously stored up in the walls of the chambers in which it is contained, and there passes off from those chambers a mixture of gases and vapors containing both free chlorine and vapor 35 of hydrochloric acid. This mixture of gases and vapors passes off from *A A A A* by the horizontal channels *a a a a* into the vacant space between the masonry of the furnace and the door *F*, which vacant space is 40 seen in Fig. 6, and then passes by the channel *l*, Figs. 2, 4, and 6, into the pipe *m*, Figs. 2, 3, 4, and 6. From the pipe *m* the said mixture of gases and vapors is conveyed to apparatus for condensing out of it its vapor 45 of hydrochloric acid, and what passes off from that apparatus then goes onto apparatus for the absorption of its chlorine. The air which enters the chambers *A A A A* through apertures in the door *E* may either 50 be forced in under pressure or be drawn in by means of an aspirator. It is preferable that it should be drawn in by means of an aspirator, and that this aspirator should be placed after the chlorine-absorption apparatus. 55

When the decomposition of the oxychloride has proceeded sufficiently far, the admission of air into the working-chambers must be arrested, the door *F* must be opened, and the residual oxide contained in the chambers *A A A A* must then be discharged. That residual oxide is drawn out of the horizontal chan-

nels *a a a a* by means of a suitable rake. If need be, to facilitate the descent of the said residual oxide to the bottom of each chamber 70 *A A A A*, a tool may be introduced into the upper extremities of those chambers by the opening *II*. When the residual oxide has been completely discharged, the cover of the opening *H* must be replaced, and then, the 75 door *E* having been opened, the movable regenerative burner must be brought back into the position in which it is shown in Fig. 1, and the working-chambers of the furnace proper must then be heated up again for another operation. 80

When the apparatus is not employed for heating oxychloride of magnesium in a current of air, or for heating the material treated, whatever be that material, in a current of gas 85 or vapor, and when the material treated does not itself give off gas or vapor during the operation of heating it, neither holes in the door *E* nor the channel *l* nor the pipe *m* will be required. 90

Each working-chamber may be provided with a sight-hole capable of being opened and closed at will, through which the temperature of the contents of the narrow working-chambers may be observed. Such a sight-hole is 95 shown at *y*, Fig. 1.

The details of the apparatus thus described may be varied in many ways. For example, without departing from the principle of the apparatus above described, the number of 100 working-chambers in that part of the apparatus which constitutes the furnace proper may be greater or less than four; that part of the apparatus may be so disposed that the products of combustion entering the working-chambers may pass in at their lower extremities and pass out at their upper extremities, the current of air or gas or vapor which afterward enters them doing the same; and the mode of charging the working-chambers, 105 the method of discharging those chambers, the method of closing the various openings in the furnace, and the mode of constructing and working the movable regenerative burner may all be varied from those above 110 described. Moreover, the movable burner need not necessarily be a regenerator also, though it will usually be preferable that it should be so. 115

What I claim is— 120

1. In an apparatus for heating solid bodies out of contact with products of combustion of the fuel employed, the combination of the furnace proper having entrance and discharge openings, a movable burner removably connected with the entrance-opening, the wheels on which the burner is mounted, and a wheeled truck on which the burner is supported moving toward and from the furnace, substantially as set forth. 125

2. In an apparatus for heating solid bodies out of contact with the products of combustion of the fuel employed, the combination of a furnace proper, a movable burner, and con- 130

- nections for leading the heated air and gas or the products of combustion from the burner to the furnace proper and back to the burner, substantially as described.
5. 3. In an apparatus for heating solid bodies out of contact with the products of combustion of the fuel employed, the combination of a furnace proper, consisting of one or more narrow working-chambers having thick walls, 10 the said chambers (when the apparatus contains more than one of them) not communicating with one another, but all communicating with a common combustion-chamber, a movable burner for heating the narrow chambers, and connections for leading the heated air and gas or the products of combustion from the burner to the furnace proper and back to the burner, substantially as described.
- 20 4. The combination of the furnace having thick walls and narrow passages or compartments connected at one end with a common supply-chamber and having a discharge-opening at the opposite end, doors for closing 25 said openings, a burner communicating with the entrance and discharge openings and mounted on movable supports, whereby it may be withdrawn from the furnace, the gas-supply pipe, detachable connections between the gas-supply pipe and the burner, the air- 30 pipe, and detachable connections between the air-pipe and the burner, substantially as set forth.
5. The combination of the furnace having thick walls and divided into a series of narrow compartments communicating at one end 35 with a common supply-chamber and at the opposite end with an exit-opening, the burner movable toward and from the furnace and parallel therewith and divided into a series 40 of compartments, the air-openings through which air is supplied to some of the compartments, a gas-pipe, connections between the gas-pipe and the burner, the flue, and connections between the burner and the flue for 45 carrying off the products of combustion after their passage through the furnace, substantially as set forth.

ALFRED RANGOD PECHINEY.
